UNITED STATES PATENT OFFICE.

ALBERT LAZARUS, OF NEW YORK, N. Y.

ELASTIC WAISTBAND FOR TROUSERS.

1,149,271.

Specification of Letters Patent. Patented Aug. 10, 1915.

Application filed August 21, 1914. Serial No. 857,809.

To all whom it may concern:

Be it known that I, ALBERT LAZARUS, a citizen of the United States, and residing at New York, in the county of New York and State of New York, have invented certain new and useful Improvements in Elastic Waistbands for Trousers, of which the following is a specification, such as will enable those skilled in the art to which it appertains to make and use the same.

This invention relates to waist bands for trousers, and the object thereof is to provide a pair of trousers with a waist band which is partially or wholly made of elastic material and which will securely hold the trousers in place without the necessity of using buckles, straps, suspenders or other devices of this class.

The invention is fully disclosed in the following specification, of which the accompanying drawing forms a part, in which the separate parts of my improvement are designated by suitable reference characters in each of the views, and in which:—

Figure 1 is a front view of the top part of a pair of trousers provided with my improved waist band; Fig. 2 a side view looking in the direction of the arrow 2 in Fig. 1; Fig. 3 a view of a fabric sheet having both warp and woof cords of elastic material which cross each other at right angles and from which a waist band may be cut on the bias, so that the waist band will have elastic cords running diagonally in both directions and crossing each other at right angles; Fig. 4 a view showing a waist band provided with elastic cords which run longitudinally thereof only; Fig. 5 a view similar to Fig. 4 but showing a waist band having elastic cords which run diagonally in both directions and which cross each other at right angles; and Fig. 6 a section on the line 6—6 of Fig. 4.

In the drawing forming part of this specification, I have shown at *a* the top part of a pair of trousers and at *b* my improved waist band, reference being made to Figs. 1 and 2, and in the construction shown, the front part *b*² of the waist band, extending between the side seams *a*² of the trousers, is composed of elastic material, while the back part *b*³ of said waist band is composed of non-elastic material. The waist band is not open at the back in the usual manner, but is

of course open at the front, as is indicated at 55 *b*⁴, and the end portions thereof are connected by buttons *c* or in any other suitable way and if at any time it is desired to make the trousers smaller or larger around the waist, the back seam, not shown, may be 60 opened for this purpose. My invention, however, is not limited to a waist band, only the front part of which is composed of elastic material and the elastic waist band may extend entirely around the trousers, if 65 desired.

In Fig. 3, I have shown at *d* a fabric sheet which is preferably of the same material as the trousers and it contains elastic cords which cross each other at right angles the 70 same as the warp and woof threads of any fabric and in practice, a waist band may be cut from this sheet on the bias, as indicated by the lines *d*² and when the waist band is made in this manner, it will have 75 elastic cords which range diagonally thereof in both directions as indicated at *d*³ and *d*⁴ in Fig. 5, or the waist band *b* may be made as shown in Fig. 4, if desired, in which the elastic cords extend only longitudinally of 80 said band. In Fig. 3, the elastic cords are indicated as in Fig. 5, by the reference characters *d*³ and *d*⁴ or in heavy black lines and in Fig. 4 they are indicated by the reference characters *d*⁵ only.

My improved waist band may be made from the fabric sheet *d* and cut wide enough to be folded longitudinally as shown in Fig. 6, or it may have a lining of any suitable material and the lining may be cut on the 90 bias to give it the desired elasticity. A waist band made in this manner will securely hold the trousers in position without the use of buckles and straps, suspenders, or any other device of this class, and my invention is not 95 limited to any particular method of weaving the fabric from which the waist band is made, the method shown in Fig. 3 and method of cutting the waist band also shown in Fig. 3 and hereinbefore described, being 100 preferred; and I also prefer that the front portion of the waist band only, as shown in Figs. 1 and 2 be made elastic.

Having fully described my invention, what I claim as new and desire to secure 105 by Letters Patent, is:—

A pair of trousers provided with a waistband of which that part only which ex-

tends from the side seams of the trousers forwardly, is composed of elastic material divided at the front to form independent end portions corresponding with the front opening in the trousers and having fastening devices.

In testimony that I claim the foregoing

as my invention I have signed my name in presence of the subscribing witnesses this 19th day of August, 1914.

ALBERT LAZARUS.
